United States Patent Office

Des. 196,119

Patented Aug. 27, 1963

196,119

INDOOR TELEVISION ANTENNA

Marvin P. Middlemark, 99-05 63rd Drive,
Rego Park, N.Y.

Filed Mar. 14, 1963, Ser. No. 73,975

Term of patent 14 years

(Cl. D26—14)

FIGURE 1 is a front perspective view of an indoor television antenna, showing my new design; FIGURE 2 is a side elevational view thereof; and

FIGURE 3 is a top plan view thereof.

I claim:

The ornamental design for an indoor television antenna, as shown.
